UNITED STATES PATENT OFFICE

2,481,433

TILTING MEANS FOR ELECTRIC FURNACES

John K. McBroom, Waukesha, Wis.

Application October 5, 1946, Serial No. 701,551

1 Claim. (Cl. 13—10)

1

This invention relates to electric furnaces and is particularly directed to tilting mechanism therefor.

Objects of this invention are to provide an electric furnace which is so made that the utmost ease is obtained in tilting the furnace whether it is charged or uncharged, and which is so made that there is a bias or tendency to tilt towards discharging position when it is charged and a bias or tendency to tilt or rock back to upright or normal position when it is empty.

In greater detail, further objects are to provide an electric furnace which is supported by segmental members located on opposite sides of the furnace and rigid with the furnace which roll on tracks and which are equipped with peripheral teeth which mesh with racks formed rigid with the tracks so that both sides of the furnace are positively moved or urged forwardly or rearwardly, and to provide a hand wheel or power member with a small pinion concentric with the segmental members and meshing with an upper rack paralleling the tracks so that when the pinion is rotated it will cause the furnace to roll or rock forward or backward as desired.

An embodiment of the invention is shown in the accompanying drawings, in which:

Figure 1 is a side elevation of the furnace showing it in upright or normal operating position, such view being partly broken away.

Figure 2 is a view showing the furnace in tilting position with parts broken away.

Figure 3 is an enlarged sectional view on the line 3—3 of Figure 1.

Referring to the drawings, it will be seen that the shell or furnace body is indicated by the reference character 1 and the top by the reference character 2. A vertical adjustable standard 3 carries a transversely extending electrode holder 4 which, in turn, carries the electrode 5. The furnace is provided with a spout or discharge member 6. It is supported by a pair of segmental flanged members 7 which are rigid with the body 1 of the furnace and are located on opposite sides thereof. These segmental members 7 are provided with segmental teeth 8. The segmental members 7 support the furnace by riding upon tracks 9 on opposite sides of the furnace carried by the standards 10. These tracks are preferably slightly upturned at their ends as indicated at 9' to provide means for preventing excessive rocking of the furnace in either direction. The tracks 9 are provided with rack teeth 11 which are formed integrally with

2

the track and which mesh with the segmental teeth 8 of the members 7.

An upper horizontal rack 12 is carried by the standards 13 or end members. A single rack 12 is provided on one side only of the furnace. This rack coacts with a small pinion 14 which is rigid with a hand wheel 15 or with a power driven member of any suitable type. For instance, the hand wheel 15 and the pinion 14 may be mounted rigidly upon a small shaft or suitable shaft 16 which is revolvably mounted in the side portion 17 of the furnace body 1.

A detent or pawl 18 is loosely pivotally carried by the shaft 16 at its bifurcated ends which ends are shown in section in Figure 3. Normally the pawl or detent 18 locks between successive teeth of the rack 12 and holds the furnace against rocking in either direction. When it is desired to rock the furnace, the pawl 18 is rocked upwardly to the dotted line position shown in Figure 1 and is arrested by means of a pin 19. When the pawl is detached, it is obvious that the furnace may be rocked.

The rocking of the furnace is accomplished by rotating the hand wheel 15 in a counter-clockwise direction as viewed in Figure 1. It is to be noted that the segmental members 7 are concentric with the pinion 14 and it is, therefore clear that the pinion 14 will travel horizontally along the rack 12 and will move the furnace to the left causing it to rock to the position shown in Figure 2. After the furnace has been emptied, it is again rocked to the position shown in Figure 1 by rotating the hand wheel 15 in a clockwise direction.

The proportion of the parts is such that when the furnace is loaded, the center of gravity is below and slightly to the left of the axis of the pinion 14, as indicated at A, see Figure 1, thus furnishing a bias or force urging the furnace towards discharging position. When the furnace is empty, the center of gravity is to the right and below the axis of the pinion 14, as indicated at B, and consequently there is a bias or force urging the furnace to the right or to its normal position when the furnace is empty. In other words, the proportion of the parts is arranged to provide a center of gravity when the furnace is empty and untilted rearwardly and below the axis of the pinion and forwardly and below the axis of the pinion when the furnace is charged and untilted.

It is to be noted that the weight of the furnace is borne by the segmental members 7 which ride

upon the tracks 9, and that there is no wedging between the segmental teeth 8 and the rack 11.

Further it is to be noted that the furnace, though relatively heavy, is very easy to rock in view of the mechanism hereinabove described as a considerable multiplication of force is obtained by the large hand wheel and the small pinion 14. These members are used merely to shift the furnace, the shifting coacting with the segmental pinions 8 and the track 9 to tilt the furnace while it is being shifted.

Thus it is clear that the minimum of effort is required in operating the furnace.

It is to be noted that the mechanism is very simple and is easy to produce and is also reliable in operation.

Although this invention has been described in considerable detail, it is to be understood that such description is intended as illustrative rather than limiting, as the invention may be variously embodied and is to be interpreted as claimed.

I claim:

An electric furnace having tilting and supporting means and having a body portion, said tilting and supporting means comprising a pair of segmental members rigid with said body portion and located on opposite sides thereof and provided with segmental teeth, stationary tracks located on opposite sides of said body portion and ar-

ranged to support said segmental members, racks adjacent said tracks meshing with the segmental teeth of said segmental members, an upper rack located above one of said first mentioned racks 5 and parallel thereto, a pinion independent of said segmental members and freely revolvably mounted about an axis coinciding with the axis of said segmental members and meshing with said upper rack, and means for rotating said pinion to thereby bodily shift said body portion and cause said body portion to tilt.

JOHN K. McBROOM.
